UNITED STATES PATENT OFFICE.

HERSCHEL F. ANDERSON, OF HUNTSVILLE, ILLINOIS.

MAIL-BAG CATCHER AND DELIVERER.

Application filed November 26, 1921. Serial No. 517,900.

To all whom it may concern:

Be it known that I, HERSCHEL F. ANDERSON, a citizen of the United States, residing at Huntsville, in the county of Schuyler and State of Illinois, have invented certain new and useful Improvements in Mail-Bag Catchers and Deliverers, of which the following is a specification.

This invention relates to improvements in mail bag catchers and deliverers and the primary object of the invention is to produce a novel and improved device for simultaneously transferring mail sacks or pouches from a moving car to a platform.

10 One of the objects of the invention is the provision of a mail sack transferring apparatus adapted to be adjustably mounted on a platform whereby mail sacks may be simultaneously delivered and received by a moving car when passing said platform in either of two directions.

15 A further and very important object of the invention is the construction of a mail bag catcher and deliverer which shall insure positive delivery and catching of a mail bag or pouch while the car is moving at a comparatively high rate of speed, the portion of the device carried by the car being adapted for swinging movement within easy reach 20 through the door, whereby the bag may be removed.

25 Another and very important object of the invention is the provision of a railway mail transferring apparatus or device adapted for installation on any type of railway mail car, the device being extremely simple in construction, easily assembled, rigid and durable, highly efficient in operation, practical and capable of being manufactured at a very 30 low cost, whereby its commercial possibilities are greatly enhanced.

35 The invention will be best understood from a consideration of the following detailed description taken in connection with the accompanying drawing forming a part 40 of this specification, with the understanding, however, that the invention is not confined to any strict conformity with the showing in the drawing, but may be changed and modified 45 so long as such changes and modifications mark no material departure from the salient features of the invention as expressed in the appended claims.

45 I attain these objects and others in the accompanying drawings, wherein:

50 Figure 1 is a fragmentary plan view of a

mail car showing the mail pouch delivering device attached to the door thereof.

55 Figure 2 is a front view showing the apparatus or device mounted on a portion of the car door and its relation with the supporting members mounted on the stationary platform.

60 Figure 3 is a vertical, sectional view through one of the supporting members attached to the platform showing the manner of supporting the bag or pouch.

65 Figure 4 is an enlarged, detail view of one of the devices mounted on a car door.

70 Referring now to the drawings, wherein like reference characters designate corresponding parts throughout the several views, 5 designates a portion of a car door of a car 5 and 6, 7, a pair of stationary supporting members on said door, adapted to receive 75 and deliver a mail bag or pouch to a moving train or car in the manner now to be set forth more specifically by reference to Figure 2 of the drawings.

75 Each supporting member 6, 7, comprises 80 a block, provided with a cutout or recess 8 therein to receive a vertical spindle 9, about which a swinging supporting arm 10 is mounted for movement on a substantially curved brace 11 disposed centrally of said 85 spindle and within the cutout portion 8 of the block. The said supporting arm 10 is provided with a spring hook 12 on its outer extremity whereby a supporting ring may be placed to which the mail bag or pouch may 90 be attached in the manner further to be set forth. The structure of the blocks or supporting members 6 and 7 is identical, with the exception that the curved brace 11 of the block 6 is provided with a spring clip 95 or clamp 13 oppositely disposed with respect to a spring clip or clamp 14 on the block 7, whereby the respective arms 10 of the supporting members may be disposed in different positions and outwardly of the 100 respective blocks to deliver and receive a mail bag or pouch from a moving train or railroad car as now to be set forth. Secured to any suitable platform 15 I have provided a pair of supporting posts or members 16, 105 17 in spaced relation, each of which is provided with a substantially T-shaped slot 18, throughout its length to permit of the vertical adjustment of the attaching and delivering device for the car. The said 110 device on each supporting member 16, 17 comprises a block 20, similar to the support.

ing blocks 6, 7 above referred to, the said block 20 in each instance also being provided with a recessed central portion 21, having a spindle 22 on which a supporting arm 23 is mounted for swinging movement on a curved brace 24, said brace also being provided with a spring clip 25 thereon for retaining the arm 23 in position. A similar spring clip 26 on the end of the supporting arm 23 is adapted to receive the supporting ring 27, which is formed with a loop 28 and attached to a mail bag or pouch 29, whereby the same may be transferred to and from the platform on the respective supporting arms, above described. In order to effect the vertical adjustment of the block 20 on the car, I have provided said blocks with threaded bolts 30, said bolts being slideable in the T-shaped groove or recess 18 and held in clamping relation by the nuts 31, passing through that portion of the blocks above the recess 21 as clearly shown by Figure 3 of the drawings.

It will be observed also that the spring clips 25 on the curved brace members 24 are also oppositely disposed, corresponding to the position of the said clips 13, 14, on the supporting blocks 6, 7, above referred to.

It will be observed that the car door shown is provided with a set of supporting blocks 6, 7, on each side of the same whereby the arms may be swung outward on either side of the door to engage a moving car on the tracks from either side. The structure is such that by vertically adjusting the blocks 20 on the platform the same may simultaneously transfer mail bag or pouches to the car when moving in either direction.

In order to show the operation of the device more clearly, reference is again had to Figure 2 of the drawing. In the position of the blocks as shown, assuming that the car is travelling in the direction indicated by the arrow, it will be observed that the arm 10, which is above the arm 23 of the supporting member 16, but below the arm 23 of the supporting member 17, may safely pass over the first mentioned supporting arm 23, by reason of sufficient clearance, and will engage a ring 27 supported on the end of the arm 23 of the supporting member 17. In a similar manner the arm 23 of the supporting member 16 is positioned below the supporting arm 10 of the block 6 and will consequently engage a ring mounted on the supporting arm 10, as the train or car passes by the platform. On the other hand, assuming that the car is travelling in the reverse direction, by simply reversing the position of the supporting blocks 20 on the members 16, 17, the same operation will take place and the mail bags may be simultaneously transferred from the platform to the car in the manner above described. The swinging movement of the supporting arm

23 is such that the same may be swung within easy reach of the mail clerk and the bag removed or a bag placed thereon, as occasion may require, to effect the delivery set forth.

In the accompanying drawings, I have illustrated my invention embodied in one form by way of example, and which in practice has been found to be highly satisfactory in obtaining the desired results. It will be obvious however, that other embodiments may be adopted, and that various changes in the details of construction may be resorted to by those skilled in the art without departing from the spirit and scope of the invention. It is furthermore understood that the invention is not necessarily limited or restricted to the precise elements shown except in so far as such limitations are specified in the subject matter being claimed.

Having thus described and illustrated my invention, what I claim as new and desire to secure by Letters Patent is:

1. A mail bag catcher and deliverer, in combination with a stationary platform and mail car, comprising a pair of oppositely disposed mail bag supporting arms swingingly supported on the car, vertically adjustable spaced blocks having swinging arms attached to the platform, said last mentioned arms adapted for movement outwardly of the platform and above or below the car supported mail bag supporting arms, whereby mail bags may be simultaneously delivered from one pair of arms to the other when the car is moving in either direction.

2. A mail bag catcher and deliverer, in combination with a stationary platform and mail car, comprising a pair of blocks and outwardly swinging mail bag supporting arms carried thereby on said car, a second pair of blocks and mail bag supporting arms vertically adjustable with respect to the platform whereby the position thereof in a horizontal plane can be varied, each of said blocks having a central recess and a spindle secured therein, a curved brace supporting member within the recess for supporting the arms, spring clips on said brace members for holding the pairs of supporting arms in oppositely disposed positions, whereby the mail bags may be simultaneously transferred from one pair of arms to the other when the car is moving in either direction.

3. A mail bag catcher and deliverer in combination with a stationary platform and mail car, comprising a pair of recessed blocks and outwardly swinging arms carried thereby, spring clips on the ends of said arms and a mail bag supporting ring adapted to be held by said clips, a second pair of recessed blocks having similar supporting arms and clips thereon independently adjustable on the platform whereby

either of said last mentioned arms may be raised or lowered to cooperate with the first mentioned arms to simultaneously transfer mail bags from one pair of arms to the other 5 when the car is moving in either direction.

4. In a mail bag catcher and deliverer, a vertically disposed supporting standard having a longitudinally extending U-shaped slot therein, a block slidably mounted upon 10 the standard, headed bolts carried by the

block having the heads thereof mounted in the T-shaped slot, and a swinging arm carried by the block.

In testimony whereof I affix my signature in presence of two witnesses.

HERSCHEL F. ANDERSON.
